UNITED STATES PATENT OFFICE.

FRANK R. MILLER, OF SPRINGFIELD, ILLINOIS.

ROAD-DRAG.

1,385,789.

Specification of Letters Patent. Patented July 26, 1921.

Application filed February 27, 1920. Serial No. 361,647.

To all whom it may concern:

Be it known that I FRANK R. MILLER, a citizen of the United States, residing at Springfield, in the county of Sangamon and 5 State of Illinois, have invented a new and useful Road-Drag, of which the following is a specification.

The invention relates to road drags of sturdy construction adapted to grade and 10 finish the road surface at one going over.

The purposes of the invention (1) are to provide a main frame of improved construction; (2) to provide in conjunction with the main frame a rigid draw bar adapted to 15 withstand heavy transverse strains without yielding, and a commodious platform stiffening the main frame and the drawbar; (3) to provide a rear drag-unit comprising two sections having a flexible connection with 20 the main frame and a hinge connection with each other, said rear-drag unit being adapted to conform to a road surface sloping from the center outwardly to the right and to the left; (4) to provide side-drag-units one at 25 each end of the main frame, inclined at an angle relative to the line of travel of the machine and flexibly connected with the main frame; (5) to provide improved means for 30 flexibly connecting the respective drag-units with the main frame; (6) to provide improved means for separately raising the respective drag-units and supporting each drag-unit in its raised position; (7) to provide improved means for flexibly connecting 35 the side drag-units with the forward terminal part of the draw-bar; (8) and to provide other improved details of construction.

With these purposes in view the invention consists in the novel features of construction and combinations of parts shown 40 in the annexed drawing to which reference is hereby made and which will now be fully described and finally recited in the claims.

Figure 1, is a perspective view of road drag embodying my invention, looking from the front toward the rear, and shows the drag units in their raised position.

Fig. 2, is a perspective view of the same machine looking from the rear toward the front, and shows the drag-units in their extended or operating position.

Fig. 3, is a top plan of the same machine.

Fig. 4, is a vertical section on the line 4, 4, of Fig. 3.

55

The main frame.

The main frame is preferably a rectangular structure of bar iron of suitable dimensions, comprising side bars 10, end bars 12 and intermediate bars 13 all firmly united. 60 The side bars 10 project outwardly a considerable distance beyond the end bars and the inner ends of the lifting frame members 15 are hinged on the outwardly projecting parts of the side bars, as will be 65 described later.

The axle 16 is suspended on the intermediate bars 13 by loops 17, (Fig. 4) which extend downwardly through straps 18 and have screw threaded terminals 19. Nuts 70 20 screwing on the terminals 19 securely unite the parts 13, 16, 17 and 18. The wheels 21 rotate on spindles at the respective ends of the axle. The axle is connected with the frame as described in order that 75 relatively low supporting wheels may be used, so that the tractor pulling the drag may have an approximately level pull on the drag.

Draw bar and platform structure.

80

The draw-bar and platform structure comprises angle bars 22 close together at their front ends and diverged rearwardly as shown, and metal plates 27 permanently 85 attached to the angle bars and to the main frame. The plates constitute a platform for the operator and brace and stiffen the structure. A transverse plate 23 (Fig. 3) is firmly attached at the forward end of the angle bars 22, and has notches 24 in which links 28 engage to prevent the links from slipping on the plate. A clevis 25 is firmly attached to the angle bars and to the plate 23. A coupling pin 26, serves to connect the 90 clevis with the tractor which pulls the machine.

Drag-units and lifting frames.

There are two single drag-units, one at 100 each end of the main frame; and a double drag-unit at the rear of the main frame.

The single or lateral drag-units are both alike, so a description of one will suffice for both.

Each lateral drag-unit comprises longitudinal angle bars 29 of equal length and parallel to each other but in such relation to each other that the outer end of the front bar projects outwardly somewhat beyond the outer end of the rear bar; and the inner end of the rear bar projects inwardly somewhat beyond the inner end of the front bar.

Scaper blades 30 are detachably connected on the front of the respective longitudinal bars.

Channel bars 31 are at right angles to the bars 29 and are fixed thereon.

A channel plate 32 is fixed on the bars 29 and is inclined relative to the bars to such extent that when the drag-unit is raised the channel plate will occupy a horizontal position; furthermore the channel plate is somewhat outside the center of gravity of the drag-unit so that during the raising of the drag-unit its inner end will gravitate downward and will remain on the ground until the outer end of the drag-unit has been raised almost to a vertical position, thus availing of the leverage due to the turning of the inner end of the drag-unit on the ground, and avoiding the dead lift which otherwise would be necessary to raise the drag unit bodily. The downwardly gravitating drag-unit and the lifting means co-acting therewith as described, are important features of my invention. Box loops 33 transverse to the channel plate 32 are fixed thereon and are spaced apart from each other so that the side members of the lifting frame will lie close to the outside of the respective box-loops and the transverse central member of the lifting frame will lie under the box loops.

Each lifting frame, is formed from a single rod bent in U-shape, (Fig. 3) and comprises side members 15 and a transverse member 34. The side members 15 have curved parts 35 adjacent to the transverse member 34. Adjacent to the ends of the respective members 15 are transverse holes 36 (not shown) accommodating the rod 38. A gas pipe 37 extends across the lifting frame between the side members. The rod 38 extends through the outwardly extended parts of the side bars 10 of the main frame, through the pipe 37, and through the holes 36. The pipe 37 prevents the members 15 from sliding inward on the rod. The rod 38 extending through the side bars 10 and through the side members 15 forms a hinge connection of the lifting frame with the main frame.

When the lateral drag-units are extended as shown in Fig. 2, the member 34 will lie in the channel of the plate 32 and will not

interfere with necessary slight vertical movement of the drag-unit relative to the ground on which it is operating, and the side members of the lifting frame will engage on the outer edges of the box loops to prevent the drag-unit from sliding forwardly or rearwardly.

When the drag-unit is in the raised position shown in Fig. 1, the lifting frame will be approximately vertical, the drag-structure will be supported on the member 34 of the lifting frame, and the curved members 35 engaging on the outer edges of the box loops will prevent forward and rearward oscillation of the suspended drag-unit.

The flexible connection of the lifting frame with the main frame, and the flexible connection of the drag structure with the lifting frame, are important features of my invention.

Loops 39 are fixed on the front angle bar 29. Draft chains 40 are connected with the links 28 and the loops 39. The chains 40 are of different lengths according to the inclination of the drag-units relative to the line of travel of the machine.

The rear drag-unit comprises two sections 41 and 42. A rod 43 extends through the lapped side-rails of the sections and forms a hinge connection of the sections. Each of the sections 41 and 42 is similar to the lateral drag-units already described, except that the channel bars at the respective ends of the section and the intermediate channel plate, are all at right angles to the side rails of the section; and except that on the channel plate of the section there is only one box loop instead of the two box loops used on the channel plate of the lateral drag-unit.

The central member 44 of the lifting frame extends through two box loops 45, one on the channel plate 46 and the other on the channel plate 47, so that the lifting frame will operate to simultaneously raise the united sections.

A bar 48 permanently attached to the rear rail of the main frame has terminal members 49 at right angles to the body of the bar. A rod 50 extends through the members 49, through the side members of the lifting frame, and through a gas pipe 51 extending between the side members of the lifting frame; and the pipe and bolt 120 form a hinge connection of the lifting frame with the main frame.

Windlass and bumper units.

There are three windlass and bumper units which co-operate with the respective drag-units. Each windlass and bumper unit comprises among other things; stationary standards 52; braces 53 and a box 54 supported on the standard and extended 130

outwardly in line with the drag-unit with which the windlass and bumper unit coöperates. The box is at such height above the hinge connection between the lifting frame 5 and the main frame that when the drag-unit is raised, its intermediate channel plate will stop against the outer end of the box and the box will prevent the drag-unit from swinging too far inward, thus avoiding injury to the operator, or damage to machine, 10 which might result from excessive inward swinging of the drag-unit.

A rotative shaft 55 (Fig. 4) extends across the box 54. A hand wheel 56 and a ratchet wheel 57 are secured on the shaft. A pawl 58 (Fig. 1) pivoted on the side of the box is adapted to engage the teeth of the ratchet wheel. A wire rope 59 has one end connected with the stationary structure; the rope 20 extends around a sheave 60 (Fig. 3) which is connected with the transverse member of the lifting frame by a suitable connecting device 61 and the other end of the rope is attached to the shaft 55. Upon clockwise rotation 25 of the shaft the rope will be wound around the shaft and will pull on the transverse member of the lifting frame to turn the lifting frame upwardly on its hinge to raise the drag-unit to the desired extent, and 30 when it has been raised the pawl 58 will engage the ratchet wheel 57 and keep the drag unit in its raised position. To lower the drag-unit the pawl will be released and the hand wheel 56 will be slowly rotated 35 counter clockwise to permit gradual lowering of the drag-unit.

Operation.

When crossing a bridge, or going through 10 a gate, or traveling on the road, but not operating thereon, all the drag-units will be raised as shown in Fig. 1.

When working on the road the proper hand wheel 56 may be used to raise either 45 lateral drag-unit to pass an obstruction or to permit a vehicle to pass; and when it has passed the same hand wheel may be used to again lower the drag-unit.

I do not restrict my claims to the exact 50 details of construction herein set forth since it is obvious that minor details may be varied and still keep within the scope of my invention.

Claims.

55 Having fully described my invention what I claim as new and desire to secure by Letters Patent is:

1. In a road drag, the combination of a drawbar structure comprising angle bars 60 diverged from the front toward the rear; a transverse bar uniting the converged ends of the angle bars; and having a pair of notches adjacent to each end of said transverse bar; a main frame; wheels supporting 65 the main frame; two laterally extendible

drag-units hinged at the respective ends of the main frame, and two pairs of chains engaging in the pairs of notches adjacent to the respective ends of said transverse bar, one chain of each pair being attached adjacent to the outer end of one lateral drag-unit and the other chain of the same pair being attached adjacent to the inner end of the same drag-unit, to exert uniform forward pull at both ends of the respective extended drag units. 70 75

2. In a road drag, a drag-unit comprising side bars, cross bars uniting said side bars, an intermediate plate inclined relative to said side bars and box loops attached to 80 said intermediate plate; in combination with a main frame and a lifting frame extending through said box loops and having a hinge connection with the main frame.

3. In a road drag, the combination of a 85 main frame comprising longitudinal bars and cross bars; a lifting frame having its terminals between the termini of the longitudinal bars of the main frame; a pipe between the terminals of the lifting frame and 90 holding them apart from each other; a rod extending through said pipe and through the longitudinal bars and preventing spreading of said longitudinal bars; and a laterally extendible drag-unit supported on 95 said lifting frame.

4. In a road drag, the combination of a main frame; a forwardly extended draw bar fixed centrally on the main frame; lateral drag units at the respective ends of the 100 main frame; a rear drag unit comprising two sections flexibly united by a hinge device in line with the draw bar; means for simultaneously raising and supporting both sections of the rear drag unit in raised position; and means for separately raising and supporting the respective lateral drag-units. 105

5. A road-drag comprising a main frame and supporting wheels; a forwardly extended draw-bar fixed centrally on the main 110 frame; a rear drag-unit consisting of two drag-members flexibly connected with each other by a hinge device in line with the draw-bar; box loops fixed on the respective drag-members; a lifting frame hinged on the main frame and extending through said box loops; and means for turning said lifting frame upwardly on its hinge to simultaneously raise both drag-members and support them in their raised position. 115 120

6. A road drag comprising supporting wheels; a main frame extended laterally beyond the supporting wheels; two lateral drag units, one at each end of the main frame; box loops fixed on the respective 125 lateral drag units; hinged lifting frames at the respective ends of the main frame and extending through the respective box loops; means for turning the respective lifting frames upwardly; a forwardly extended 130

draw bar fixed centrally on the main frame; a rear drag unit consisting of two drag-frames united by a hinge device in line with the draw-bar and extended laterally be-
5 yond the respective ends of the main frame; box loops fixed on the respective drag frames; a lifting frame hinged on the main frame and extending through both of said box loops and adapted to raise both drag
10 frames simultaneously and support them in

their raised position and means for turning said last named lifting frame upwardly.

In witness whereof I have hereunto signed my name at Springfield, Illinois, this 19th day of February, 1920.

FRANK R. MILLER.
